US00D734751S

(12) **United States Design Patent**
Oberpriller et al.

(10) **Patent No.:** **US D734,751 S**
(45) **Date of Patent:** **** Jul. 21, 2015**

(54) **IMAGING TERMINAL**

(71) Applicant: **HAND HELD PRODUCTS, INC.**, Fort Mill, SC (US)

(72) Inventors: **Mark L. Oberpriller**, Atlanta, GA (US); **Timothy R. Fitch**, Syracuse, NY (US); **Donna M. Fletcher**, Auburn, NY (US)

(73) Assignee: **Hand Held Products, Inc.**, Fort Mill, SC (US)

(**) Term: **14 Years**

(21) Appl. No.: **29/486,759**

(22) Filed: **Apr. 2, 2014**

Related U.S. Application Data

(60) Division of application No. 29/446,944, filed on Feb. 28, 2013, now Pat. No. Des. 702,237, which is a continuation of application No. 13/739,576, filed on Jan. 11, 2013, now Pat. No. 8,777,109.

(57)

CLAIM

The ornamental design for an imaging terminal, as shown and described.

DESCRIPTION

FIG. 1 is a perspective view of an imaging terminal in accordance with the new design;

FIG. 2 is a front elevational view thereof;

FIG. 3 is a right side elevational view thereof;

FIG. 4 is a left side elevational view thereof;

FIG. 5 is a rear elevational view thereof; and,

FIG. 6 is a top view thereof.

Broken lines and entirely unshaded portions contained within broken lines are not claimed.

1 Claim, 6 Drawing Sheets
